TO THE PATENT AND LICENSING CORPORATION, OF BOSTON, MASSACHUSETTS, A
CORPORATION OF MASSACHUSETTS

ROOFING AND METHOD OF MAKING SAME

Application filed October 20, 1926. Serial No. 142,820.

The invention is more particularly directed to flexible roofing material, and in its specific embodiment comprises a flexible roofing sheet having on its surface in predetermined areas, 5 granular material, said sheet being folded upon itself, and the opposed folded facings carrying a granular material united together by means of an adhesive to provide a folded sheet the interior of which carries granular 10 filling material.

An object of the invention is to provide a relatively light weight thick butt tapered flexible roofing element of desired size and shape.

15 The method of producing such a product briefly stated, comprises applying and uniting to a surface of flexible roofing sheet granular material in spaced areas. The sheet may be then folded, and the opposed faces of 20 both the sheet and the granular material firmly united by means of an adhesive. The application of the granular material to a surface of the unfolded sheet is carefully regulated to concentrate said granular material 25 in the interior of the folded sheet in greatest bulk or amount adjacent the folded edge, to produce a thick butt tapered roofing element.

As one of the features of the invention, the folded sheet is immersed in suitable water- 30 proofing material to coat all edges and surfaces, and form an impervious enveloping coating about the folded sheet, which will prevent de-lamination. The usual granular surfacing may be imbedded in this coating.

35 Other advantages and objects of the present method and product will be hereinafter more particularly brought out.

In the drawings, Fig. 1 is a plan view of an unfolded sheet provided with spaced 40 areas of granular material.

Fig. 2 is a cross sectional view on line 2—2 of Fig. 1.

Fig. 3 is a cross sectional view illustrating the method of folding the sheet upon itself.

45 Fig. 4 is a cross sectional view illustrating a thick butt tapered roofing element, made in accordance with the present invention immediately after folding.

Fig. 5 is a view similar to Fig. 4 showing 50 the sealing or enveloping coating and granu-

lar surfacing applied to the folded element shown in Fig. 4.

Referring more in detail to the drawings, 1 designates a sheet of flexible roofing material, which may comprise felt, saturated or 55 impregnated in the usual way, with a waterproofing material, for instance, asphalt. One surface of this sheet is coated with an adhesive material in predetermined areas, or according to a predetermined design. Granular material designated at 2 which may comprise sawdust, cork, ground up roofing waste, or mineral granules, is imbedded in the coated areas.

In Fig. 1 these areas are illustrated as taking the form of longitudinally spaced strips 3 and 4 leaving intermediate the unsurfaced strip 5 and marginal bands 6 and 7 of uncoated saturated felt. It is to be understood of course, that the present invention is not 65 limited to applying and uniting the granular surfacing material in any regular design, for instance, it may be found desirable to imbed this granular material in irregular areas of different design than longitudinal 70 strips. It is also to be noted that Fig. 1 illustrates strip 3 as being materially wider than strip 4. It is of course, understood that this is merely for the purpose of illustration, as the width of these two strips may vary widely 75 relative to each other within the contemplation of the invention.

80 Preferably, the relative widths of the granular-free bands 5, 6 and 7 is carefully adjusted so that when the sheet is folded and the marginal edges 6 and 7 brought together, there will be a greater bulk of granular material immediately adjacent the fold, gradually decreasing in thickness toward the other edge to provide a thick butt tapered roofing 85 element shown as a whole in Fig. 4. Before the sheet is folded, a coating of adhesive material such as asphalt, is applied to the sheet so that when the sheet is folded and the opposed surfaces of both the fold and granular 90 material brought together, adhesion will result. This adhesive material is illustrated in Figs. 4 and 5 by the numeral 8.

95 As a feature of the present invention, after the sheet has been folded, and the opposed 100

surfaces adhesively united, the folded sheet is immersed in a bath of waterproofing material to provide an impervious waterproof coating or enveloping coating for all surfaces and edges. This waterproofing material will generally be oxidized asphalt of about 220° F. melting point. The depth of immersion will vary but should cover at least that portion of the shingle which is exposed to the weather in laying.

This will prevent any tendency to de-lamination of the folded element. The usual granular surfacing material may then be imbedded in the exposed coating.

15 The coating is illustrated in Fig. 5 by the numeral 9, and the granular surfacing by the numeral 10.

It will be apparent that by varying the position or shape of the granular covered and 20 granular-free areas as shown in Fig. 1 with relation to the fold, a tapered element or stock of any particular configuration or taper can be produced.

It is also obvious that the size of the granules can be varied so that the granules which are adjacent finally to the thinnest width of the folded element, are of the smallest size, while the granular particles at the portion constituting the butt of the element are of 30 coarser size. A stock made in this way can be slated for shingle strips or cut into individual shingles, but in any event should be dipped in coating and slated in the usual way.

I claim as my invention:

35 1. The method which comprises applying and adhesively uniting granular surfacing material to a face of a flexible sheet of roofing material, folding said sheet intermediate its edges so as to bring portions of said granular surfaced face into opposed relationship.

40 2. The method which comprises applying and adhesively uniting granular material to a surface of a flexible sheet of roofing material, folding said sheet intermediate its edges and 45 joining the surfaces to incorporate the granular material in the interior of the folded sheet, and regulating the application of the granular material so that the amount of granular material in the interior of the folded sheet is materially greater adjacent the folded edge than at the opposite joined edge.

55 3. The method which comprises applying and adhesively uniting granular material to a surface of a flexible sheet of roofing material, folding said sheet intermediate its edges and joining the surfaces to incorporate the granular material in the interior of the folded sheet, regulating the application of the granular material so that the amount of 60 granular material in the interior of the folded sheet is materially greater adjacent the folded edge and at the opposite joined edge, coating the folded sheet and imbedding granular surfacing in said coating.

75 4. The method which comprises applying

and adhesively uniting cork granules to a surface of a flexible sheet of roofing material, folding said sheet intermediate its edges and joining the surfaces to incorporate the cork granules in the interior of the folded sheet. 70

5. The method which comprises applying and adhesively uniting granular material to the surface of a flexible roofing sheet in the form of spaced areas intermediate the side edges, folding said sheet on a line corresponding to a space between predetermined granular surfaced areas and joining the opposite marginal granular-free bands to incorporate the granular material in the interior 75 of the folded sheet.

6. The method which comprises applying and adhesively uniting granular material to the surface of a flexible roofing sheet in the form of spaced areas intermediate the side edges, folding said sheet on a line corresponding to a space between predetermined granular surfaced areas and joining the opposite marginal granular-free bands to incorporate the granular material in the interior of the folded sheet, so regulating the width of the granular surfaced areas relative each other as to concentrate in the folded sheet the granular material in greatest bulk adjacent the folded edge to produce a thickened butt at said edge relative the opposite edge. 90

7. The method which comprises applying and adhesively uniting granular material to a flexible roofing sheet in spaced longitudinal areas intermediate the side edges thereof to produce a sheet having spaced bands of granular material and marginal and intermediate bands free of said granular material, folding said sheet on a line corresponding to a predetermined intermediate band free of said granular material and joining said granular free marginal edges to incorporate the granular material in the interior of said folded sheet in greatest bulk adjacent the folded edge, whereby a thickened butt is produced at said folded edge. 105

8. The method which comprises applying and adhesively uniting granular material to a flexible roofing sheet in spaced longitudinal areas intermediate the side edges thereof, said strips being of different width relative each other, to produce a sheet having spaced bands of granular material and marginal and intermediate bands free of said granular material, folding said sheet on a line corresponding to a predetermined intermediate band free of said granular material and joining said granular-free marginal edges to incorporate the granular material in the interior of said folded sheet whereby a thickened butt is produced at said folded edge, the relative widths of said bands of granular material being so regulated as to produce a folded sheet tapering from the thickened butt to the joined edges. 115

9. The method which comprises applying 130

- and adhesively uniting cork granules to a flexible roofing sheet in spaced longitudinal areas intermediate the side edges thereof to produce a sheet having spaced bands of cork granules and marginal and intermediate bands free of said cork granules, folding said sheet on a line corresponding to a predetermined intermediate band free of said cork granules and joining said free marginal edges to incorporate the cork granules in the interior of said folded sheet in greatest bulk adjacent the folded edge, whereby a thickened butt is produced at said folded edge. 10. The method which comprises applying and adhesively uniting granular material to a flexible roofing sheet in spaced longitudinal areas intermediate the side edges thereof to produce a sheet having spaced bands of granular material and marginal and intermediate bands free of said granular material, folding said sheet on a line corresponding to a predetermined intermediate band free of said granular material and joining said granular-free marginal edges to incorporate the granular material in the interior of said folded sheet in greatest bulk adjacent the folded edge, whereby a thickened butt is produced at said folded edge: 11. The method which comprises applying and adhesively uniting intermediate the edges of a flexible roofing sheet spaced stripes of granular material to produce a sheet exhibiting intermediate and marginal bands free of such granular material, in folding said sheet on an intermediate granular-free line and forcing the opposite folded surfaces together to incorporate the granular material in the interior of the sheet and unite the granular surfaced areas, and regulating said granular surfaced stripes relative to each other so as to concentrate the granular material in greatest bulk in the interior of the folded sheet adjacent the folded edge, whereby to produce a thickened butt at said edge. 12. A method which comprises applying and adhesively uniting granular material to the surface of a flexible sheet of roofing material, folding said sheet intermediate its edges and joining the surfaces to incorporate the granular material in the interior of the folded sheet, coating all exposed edges and surfaces with an impervious envelope of high melting point asphalt and imbedding granular material in said coating. 13. The method which comprises applying and adhesively uniting granular surfacing material to a face of a flexible sheet of roofing material, folding said sheet upon itself so as to bring sections of said surfaced face into opposed relationship, and coating the thus laminated base with high melting point asphalt to prevent delamination. 14. The method of producing thick butt tapered roofing elements which comprises surfacing spaced areas of a face of a felted fi-
- brous foundation with granular material, folding said foundation upon itself on a line intermediate said surfaced areas so as to bring said surfaced areas into contacting relation and applying a sealing coat of asphalt to the edges and surfaces of the folded element which are to be exposed to the weather when said element is laid with others on a roof. 15. The method of producing thick butt tapered roofing elements which comprises surfacing spaced areas of a felted fibrous foundation with granular material, one of said surfaced areas being of greater extent in one direction than the adjacent area, folding said foundation upon itself on a line intermediate said surfaced areas so as to bring said surfaced areas into contacting relation, and applying a sealing coat of asphalt to the edges and surfaces of the folded element which are to be exposed to the weather when said element is laid with others on a roof. 16. As an article of manufacture, roofing material comprising a section of granular surfaced fibrous roofing base folded upon itself so as to bring portions of the surfaced face thereof into opposed contacting relationship with each other, said opposed portions being adherently united by a layer of waterproof adhesive. 17. Roofing material comprising a section of granular surfaced fibrous roofing base folded upon itself so as to bring portions of the surfaced face thereof into opposed contacting relationship with each other, the folded product having a sealing coat of asphalt on all surfaces and edges thereof which are to be exposed to the weather when laid on a roof. 18. Roofing material comprising a section of granular surfaced fibrous roofing base folded upon itself so as to bring portions of the surfaced face thereof into opposed contacting relationship with each other, the folded product having a sealing coat of asphalt on all surfaces and edges thereof which are to be exposed to the weather when laid on a roof, and a layer of grit partially imbedded in said sealing coat. 19. Roofing material comprising a section of granular surfaced fibrous roofing base folded upon itself so as to bring portions of the surfaced face thereof into opposed contacting relationship with each other, a granular surfacing on one of said portions extending for a greater distance transversely of said fold than the surfacing on the opposed portion. 20. Roofing material comprising a section of granular surfaced fibrous roofing base folded upon itself so as to bring portions of the surfaced face thereof into opposed contacting relationship with each other, the granular surfacing on said folded portions being thickest adjacent the fold.

21. Roofing material comprising a section of granular surfaced fibrous roofing base folded upon itself so as to bring portions of the surfaced face thereof into opposed contacting relationship with each other, the granular surfacing on said folded portions being thickest adjacent the fold, and gradually diminishing in thickness in a direction away from the fold.
- 10 22. Roofing material comprising a section of granular surfaced fibrous roofing base folded upon itself so as to bring portions of the surfaced face thereof into opposed contacting relationship with each other, the granular surfacing on one of said portions extending for a greater distance transversely of said fold than the surfacing on the opposed portion, and the folded product having a sealing coat of asphalt on all surfaces and edges thereof which are to be exposed to the weather when the product is applied on a roof.
- 15 23. Roofing material comprising a section of granular surfaced fibrous roofing base folded upon itself so as to bring portions of the surfaced face thereof into opposed contacting relationship with each other, the granular surfacing on said folded portions being thickest adjacent the fold, and the folded product having a sealing coat of asphalt on all surfaces and edges thereof which are to be exposed to the weather when the product is applied on a roof.
- 20 24. Roofing material comprising a section of granular surfaced fibrous roofing base folded upon itself so as to bring portions of the surfaced face thereof into opposed contacting relationship with each other, the granular surfacing on said folded portions gradually diminishing in thickness in a direction away from the fold and terminating inwardly of the opposite edge of the folded product.
- 25 25. A waterproof covering comprising laminæ of asphalt saturated and coated and granular surfaced roofing base, the laminæ being united with the surfaced faces thereof in opposing contact, and the granular surfacing on the interior of the laminated structure being thicker at one edge thereof than at the opposite edge.

LESTER KIRSCHBRAUN.
